DOUBLE GLAZED WINDOW

William Owen, Pittsburgh, Pa., assignor to Pittsburgh Plate Glass Company, Allegheny County, Pa., a corporation of Pennsylvania

Application April 22, 1938, Serial No. 203,571

1 Claim. (Cl. 20—56.5)

The invention relates to double glazed windows, and particularly to means for applying a second sheet or pane of glass to existing single glazed windows employing wood sash. The invention has for its principal objects the provision of an improved construction of the type specified, (1) which is easily applied and removed from the ordinary sash, (2) which requires no screws or carpentry work in installing, (3) which is secure and tight, (4) which can be applied without difficulty even though there is some departure from exact pane size due to inaccuracy in cutting, and (5) which is inexpensive and durable. Certain embodiments of the invention are illustrated in the accompanying drawing, wherein:

Figure 1 is a partial front elevation of the construction. Fig. 2 is a section on the line II—II of Fig. 1. And Figs. 3, 4 and 5 are sections through modifications.

Referring to the drawing, 6 is the window sash of wood and 7 is a pane of glass mounted on the outer side of the frame and held in position by putty 8 or other suitable means which maintain this pane in a relatively permanent position in the sash. Mounted on the inner side of the pane 7 in parallel therewith is the second pane of glass 9 carried in a sheet metal frame 10, such sheet metal frame being provided with a channel 11 carrying the edges of the pane 9. A strip of rubber 12, U-shape in cross section serves to cushion the glass in the channel, and if desired, other suitable cushioning materials may be employed. The frame 10 is provided with a pair of spring flanges 13 and 14 which engage the wall 15 surrounding the sash opening, as shown. The flange 13 acts as a spacer between the two panes of glass and has its lower end recurved, as indicated at 16. This flange is so proportioned with respect to the sash opening that when the frame 10 is pushed into position, the flange 15 presses with considerable force against the wall of the sash, the purpose being to insure a seal by this pressure and also to assist in maintaining the frame against accidental displacement. The other flange 14 engages the sash outward of the flange 13, being seated on one of the steps 16, constituting the customary ornamentation of the ordinary sash. It is possible to engage the end of the flange 14 on one of several of the steps, depending upon the amount of force applied in pressing the flange 14 inward, and it is the spring pressure which is thus exerted upon the sash by this flange which gives the main anchoring effect of the frame in the sash. The frame is preferably made in four sections, as indicated in Fig. 1, such

sections meeting along the bevel lines 17. If desired, they may be soldered together along these lines, although it is practical to use the structure without attaching the sections together, this being the simpler and cheaper method of applying the construction.

Due to the spring character of the flanges 13 and 14, it is possible to use the frame, even though it is not a perfect fit in the sash, since the flanges will give and permit them to be forced into position. It is thus not necessary to cut the pane 9 to size with the same degree of accuracy as is necessary in structures which have only a small amount of yield, such as rubber mountings which have heretofore been proposed. Further, due to the two point engagement of the flanges 13 and 14 with the sash, the danger of accidental displacement of the frame is materially reduced. Any outward force as applied to the pane 9, due to air suction or other causes, is strongly resisted by the flange 14 since the outward movement of the pane tends to force the end of the flange more strongly against the step of the sash with which it engages.

Fig. 3 illustrates a modification which is the same in principle as that of Figs. 1 and 2, the primary difference being in the shape of the frame, and particularly the flange 18. This flange has a V-shaped bend 19 and the extremity of the flange is provided with a rubber cushion 20 which engages the pane 7 and presses against the wall of the sash opening. The use of this rubber provides a somewhat better seal between the sash and the space between the two panes than does the recurved end 16 of the flange 13, as shown in Fig. 2.

Fig. 4 shows a further modification, in which the flanges 21 and 22 are shaped only slightly different from those of the Fig. 2 construction, the primary distinction here over the structure 40 of Fig. 2, being the use of the screws 23 extending through the flange 22 and into the sash for giving greater security to the mounting of the frame. As heretofore explained, the mounting of the sash is relatively secure without the screws, and in most cases, it is preferred to dispense with such screws because of the extra labor involved in the installation, but in special locations where additional security is required, a single screw on each side of the sash will insure positively against accidental displacement of the inner pane 9.

In the Fig. 5 construction, a strip of rubber 24 is provided as a spacer, such rubber being seated in a channel 25, which constitutes one of the flanges of the frame corresponding in function

to the flange 13 of the Fig. 2 construction. The other flange of the frame is formed by the strips 26 and 27, the upper end of the strip 26 being curved back, as indicated at 28, and constituting a part of the channel for receiving the edge of the pane 9. In this case, as in the Fig. 4 construction, the screws 29 are employed for giving greater security to the mounting of the frame in the sash.

10. What I claim is:

In combination with a window sash having a permanently mounted pane on its outer side, a removable unit mounted in the sash on its inner

side comprising a second pane in parallel with the first pane, and a sheet metal frame therefor provided with a channel receiving the edges of the second pane and having a spring flange on each side of the channel in yielding engagement with the portion of the wall of the sash opening which extends transversely of the plane of the panes, one of said flanges having its end in engagement with the first pane and cushioned with rubber so that it acts as a spacer between the 10 two panes.

WILLIAM OWEN.
